UNITED STATES PATENT OFFICE.

CHARLES MALLON, OF NEW YORK, N. Y.

WINDOW-CLEANER'S SAFETY DEVICE.

Application filed June 19, 1926. Serial No. 117,038.

This invention relates to a window cleaner's safety device, and more specifically to the supporting device or anchor which is connected to the building structure and to which the window cleaner's safety belt is adapted to be connected and disconnected.

An object of the invention is to provide a support or anchor device which is of simple construction and which may be attached or mounted in its operative position with a minimum of effort and time consumption.

A further object is to so construct the device or anchor that it will take an unusually firm grip upon the abutting part of the building structure, thus rendering the connection between the anchor and the building structure correspondingly substantial and efficient.

A further object is to so construct the device that it will fulfill the above objects without necessity for the cutting away of any of the parts of the building structure, except a single straight bore, during the operation of attaching it to the building structure.

More specifically, it is an object of this invention to provide an anchor so formed and constructed as to include biting edges for engaging against the surface of the window frame and the biting edges being adapted to bite into said surface for assisting in the support of the head when the bolt is drawn tight.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a side view of an anchor bolt constructed in accordance with this invention and showing the same as it appears in use connected with a window frame, the window frame being shown in horizontal section, and

Fig. 2 is a detail perspective view of the head end of the anchor device seen in Fig. 1. Referring to the drawings for describing

in detail the structure shown therein the reference character L indicates one of the side members of a window frame, a portion of a window, as 1, being shown in association therewith. Through the window frame L is formed a single bore 2 adapted to receive the shank of the safety bolt or anchor G. Abutting the outer surface of the window frame L is shown a portion of the masonry or other part of the building structure as 3, the angle between the outer surface of the window frame and the masonry 3 being furnished with the usual staff bead H.

The bore 2 continues through the staff bead H.

At the outer end of the bolt G is a head 4 for engaging against the outer surface of the staff bead, and at the inner end of the bolt is a nut 5 which is threaded upon the bolt and which is adapted to draw the head 4 firmly against the bead H when the nut is tightened.

The head 4 is preferably disposed at an acute angle relative to the length of the bolt and is formed with an outwardly projecting lug thereon adapted to be engaged by a part of the window cleaner's safety belt and having an auxiliary head 7 to prevent accidental detachment of said belt, as is usual in this art.

The angular disposition of the head 4 is for the purpose of disposing the lug 6 in such a position as to be more readily engaged by the belt fixture.

It has been found in practice that due to the great variation in contours of the outer surfaces of the staff beads at the side of the windows in different buildings it has been practically prohibitive to provide safety bolt heads of all of the different contours met with, and hence it has become the universal practice to make the safety bolts with heads at right angles to the length of the bolt and to cut away suitable portions of the staff bead to allow these heads to be received into the bead for a suitable distance to enable them to find a satisfactory flat support. This practice has not only resulted in considerable unnecessary expense of time and money in the operation of attaching a large number of bolts but has resulted in a positive danger in that the workman in cutting away the material of the bead, in doing the work by hand, has not always succeeded in providing a suitable flat surface to be en-

gaged by the bolt head. If the surface underlying the head engages the head only at one end there is a strong bending strain set up at the juncture of the shank and head 5 when the nut is drawn tight, said strain being detrimental to the fullest measure of efficiency of the device.

By the present invention a head is provided which is at an angle to the length of 10 the bolt and which is curved so as to be of pronounced channel shape, as at 8, on its under-surface for engaging against the surface of the staff bead. By channelling or curving the under-surface of the head substantially as illustrated said surface is made 15 to approximately conform in general contour to most of the staff beads now used and at the same time provides opposite biting edges as 9—9 which readily embed themselves or bite into the material of the beads, 20 as shown at 10 and 11 in Fig. 1, when the head is drawn up tight. This is particularly true where the curvature of the surface of the bead is of greater radius than the curvature of the channel surface 8. At the 25 same time the portion of the head which lies in the region between the biting edges is crowded and urged inwardly toward the depth of the channel, and this crowding 30 of the material of the bead, which is usually wood, of course causes the material to be somewhat condensed and thus made more firm and strong. As the material is crowded inwardly it is urged into tighter contact 35 with the shank portion of the device at a point directly adjacent the head so that a highly efficient support is thus given the head without necessity for any preliminary cutting away of material of the bead to fit the head.

By the means as illustrated the head is given a uniformly efficient grip upon the staff head. All strains are distributed evenly throughout the head and the head is accordingly given a high degree of efficiency 45 for the performance of its vital function, namely as a life saving device.

By disposing all parts of the head structure at an angle relative to the length of the bolt, so that the head may be more readily accessible to the belt device, the lug portion 6 may be maintained at minimum length, and thus be kept amply strong without wasteful use of material.

The concavity of the under-surface of the head, and the engagement of the material of the bead therein operates at all times to prevent any possible rotary movement of the bolt within the bore of the window frame and the grip of the biting edges 9 into the material of the window frame is also effective in obtaining this highly desirable result.

While there is shown, and described hereinabove, a head having only a single lug 6,

with auxiliary head 7 thereon, it will of course be understood that the number of lugs provided upon the head is merely a matter of choice, as is also the shape or form of the lug or lugs.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. A device of the class described comprising a shank portion and a head portion, a clamp nut threaded upon the shank portion by which to draw the head portion into operative position, the head portion having a lug projecting therefrom to receive the window cleaner's usual belt device, and the under-surface of the head being of channel shape providing oppositely disposed edges thereon adapted to bite into the material of the window frame under the pull of the clamp nut.

2. A device of the class described comprising a shank portion and a head portion, a clamp nut threaded upon the shank portion by which to draw the head portion into operative position, the head portion being disposed at an angle relative to the length of the shank portion and having a lug projecting therefrom to receive the window cleaner's usual belt device, and the under-surface of the head being of channel shape providing oppositely disposed edges thereon adapted to bite into the material of the window frame under the pull of the clamp nut.

3. A device of the class described comprising a shank portion and a head portion, a clamp nut threaded upon the shank portion by which to draw the head portion into operative position, the head portion being disposed at an angle relative to the length of the shank portion and having a lug projecting therefrom to receive the window cleaner's usual belt device, and the under-surface of the head being shaped to provide a pair of marginal edges spaced apart in parallel relation thereon adapted to bite into the material of the window frame under the pull of the clamp nut.

4. A device of the class described comprising a shank portion and a head portion, clamp means provided upon the shank portion by which to draw the head portion into engagement with part of a window frame, the head portion having a lug projecting therefrom to receive the window cleaner's usual belt device, said lug projecting angularly in one direction with respect to the length of the shank portion, the remainder

- of the head portion being elongated in a direction at right angles to the length of both the shank portion and said lug, and the under-surface of the head having longitudinally extending portions thereon spaced apart adapted to bite into the material of the window frame under the pull of the clamp means, said under-surface being shaped to dispose one of said longitudinally extending portions relatively nearer to the clamp means than the other and to provide a curved surface between said longitudinally extending portions to conform to the underlying surface of the window frame.
- 5 5. In a device of the class described, comprising a head having a single bolt-like shank portion extending from the under-surface thereof and having clamp means connected with said bolt by which to draw

the under-surface of the head against a surface portion of a window frame when said shank is in position extending through an opening in the window frame, and a lug projecting from said head in a direction at an angle to the length of the shank, the combination therewith of means for retaining the head against rotary movement with respect to the window frame, said means consisting in that said head is elongated in a direction transverse to the length of both 25 said shank and said lug and also in that the under-surface of said head is curved transversely of its length to conform to a curvature of the engaged surface of the window frame.

20 30 35 In testimony whereof I affix my signature.

CHARLES MALLON.
